(57) CLAIM

The ornamental design for a glove dispensing assembly with elastic band strap as shown and described.

DESCRIPTION

FIG. 1 is a perspective view of the glove dispensing assembly with elastic band strap;

FIG. 2 is a front view of the glove dispensing assembly with elastic band strap of FIG. 1;

FIG. 3 is a rear view of the glove dispensing assembly with elastic band strap of FIG. 1;

FIG. 4 is a right side view of the glove dispensing assembly with elastic band strap of FIG. 1;

FIG. 5 is a left side view of the glove dispensing assembly with elastic band strap of FIG. 1;

FIG. 6 is a top view of the glove dispensing assembly with elastic band strap of FIG. 1; and,

FIG. 7 is a bottom view of the glove dispensing assembly with elastic band strap of FIG. 1.

The broken lines illustrate portions of the glove dispensing assembly with elastic band strap that form no part of the claim.

1 Claim, 7 Drawing Sheets
